FOOTAGE INDICATOR FOR MOTION-PICTURE APPARATUS

Edward S. McKee, Rochester, N. Y., assignor to
Eastman Kodak Company, Rochester, N. Y., a
corporation of New Jersey

Application December 2, 1949, Serial No. 130,669

3 Claims. (Cl. 235—103)

1

This invention relates to a ratchet-type assembly, and more particularly to a ratchet-type footage indicator for use with motion picture apparatus.

Footage indicators of the ratchet type are well known and as used in motion picture apparatus are generally mounted on the casing of the apparatus with the actuating mechanism mounted on the internal mechanism plate or block of the apparatus. The visible or outer scale of such indicators is positively driven and a holding member usually engages the ratchet to prevent retrograde movement of the ratchet and scale. As a result, the scale can be rotated in only one direction to return it to its zero or starting position, irrespective of the distance that the zero point may have been moved from the index mark. In the present invention this difficulty has been overcome by providing a frictional connection between the scale or its rotating member and the means for intermittently rotating said member.

The primary object of the invention, therefore, is the provision of a ratchet assembly in which the intermittent rotation of the ratchet member is frictionally transmitted to the rotatable or driven member on which the indicating means is secured.

Another object of the invention is the provision of a ratchet type of footage indicator in which a resilient means frictionally transmits the unidirectional rotation of the ratchet member to the indicating means and permits manual rotation of the indicating means in either direction independently of the ratchet member.

Still another object of the invention is the provision of a ratchet type of footage indicator in which the ratchet member, the actuating member for the ratchet member, and the resilient means for frictionally transmitting the motion of the ratchet are assembled on the driven member for the indicating means to provide a compact and easily assembled indicator.

Other and further objects of the invention will be suggested to those skilled in the art by the description which follows:

The above and other objects of the invention are embodied in a ratchet assembly comprising a driven member, an indicating means on said driven member and rotatable therewith, an intermediate drive member rotatably mounted on said driven member and having a toothed periphery, an actuating member pivotally mounted on said driven member and having an arm adapted upon movement thereof to pivot said actuating mem-

2

ber and a second arm in engagement with said toothed periphery and adapted upon movement of said first-mentioned arm to rotate said intermediate drive member, a holding means for frictionally engaging said toothed periphery to prevent retrograde movement of said intermediate drive member, and resilient means frictionally engaging said driven member for rotating said driven member upon movement of said first-mentioned arm and for permitting said indicating means to be rotated independently of said intermediate drive member.

Reference is now made to the accompanying drawing wherein similar reference numerals designate similar parts and wherein:

Figure 1 is a side elevation of a motion picture apparatus equipped with a ratchet type footage indicator according to the invention;

Figure 2 is an enlarged side elevation of the internal mechanism of the apparatus and showing the relation of the actuating mechanism for the indicator with respect to the spring motor drive of the apparatus;

Figure 3 is a vertical section taken substantially on line 3—3 of Figure 2 and showing the arrangement by which the indicating means or scale is driven and mounted with respect to the ratchet member;

Figure 4 is a detail perspective view of the actuating member and showing the relation between the rigid actuating arm and the resilient ratchet advancing arm; and

Figure 5 is a detail perspective view of the holding means for the ratchet member.

Although the improved footage indicator is illustrated and described with respect to a motion picture apparatus, it is to be understood that the invention is also applicable to all types of ratchet assemblies.

According to the illustrated embodiment of the invention, the ratchet assembly is contained within a casing 10 having side walls 11 and an edge wall 12. The drive means for actuating said ratchet assembly is mounted within said casing and includes a trip member on the periphery thereof. Such a drive means may comprise a driving member such as spring motor 13 which is rotatable about a shaft 14 extending between side walls 11 of the casing. Spring motor drum 15 contains a spring 16 which has one end attached to the drum and the other end secured to shaft 14 in a well-known manner. The trip member, or pin 17, is mounted on the periphery of drum 15 for a purpose to be described herein-after.

The ratchet assembly is mounted within casing 10 on the mechanism block 18, as indicated by dotted lines in Figure 1. The driven member or shaft 20 is journalled in boss 21 on block 18 and extends beyond said boss and into an aperture 22 in side wall 11. The shaft is maintained in proper relation to wall 11 by the spaced retaining members 23 and is provided with a third retaining member 24 between block 18 and wall 11 for a purpose to be described hereinafter. Such retaining members may be of the split expansion type which, when assembled, are seated in spaced grooves 25 in shaft 20. At its outer end shaft 20 is provided with flats 26 and a tapped hole 27.

The indicating means or scale disc 28 is provided with an aperture 29 congruent to the end of shaft 20 and is secured thereto by screw 30, disc 28 and shaft 20 being rotatable as a unit. Disc 28 is contained in a well 31 provided in wall 11 with an index mark 32 thereon and has a scale and/or series of footage numerals 33 engraved on the top surface thereof. A plurality of protuberances 34 provide a means for grasping disc 28 to set the numerals 33 with respect to index 32.

The intermediate drive member or ratchet 35 is freely rotatable on shaft 20 and is provided with a toothed periphery 36. It will be noted from Figure 3 that ratchet 35 is located on shaft 20 between the spaced retaining members 23 and 24.

The actuating member 40 is also freely rotatable on shaft 20 although it is limited to an oscillating motion for intermittently advancing ratchet 35 tooth by tooth. Member 40 is provided with an extension 41 which is formed upward at each side, the left side being formed into an arm 42 with a formed over end 43 and the right side being formed upwardly, as indicated at 44, and on which a resilient arm 45 is secured. The shape and relation of arms 42 and 45 can best be understood by reference to Figures 2 and 4. When assembled, actuating member 40 is positioned on shaft 20 so that arm 42 engages the periphery of drum 15 and lies in the path of pin 17 and arm 45 engages mechanism block 18 with outer end 46 and toothed periphery 36 with the inner end 47, as shown in Figure 2.

The holding means 50, see Figure 5, prevents retrograde motion of ratchet 35 and also is located in position by shaft 20. The holding means comprises a pair of spaced ears 51, which straddle the pin 52 on block 18 for preventing rotation or movement of said part as shaft 20 is rotated, and a formed finger 53 for frictionally engaging toothed periphery 36, as shown in Figure 2, to prevent retrograde movement of ratchet 35.

A resilient means is utilized for maintaining the ratchet in frictional engagement with shaft 20. Such a resilient member may take the form of a dished spring member 60 which with the ratchet 35 is located on shaft 20 between the spaced retaining members 23 and 24. The force of spring 60 urges ratchet 35 into frictional engagement with member 24 which, in turn, is urged against its groove to rotate shaft 20 upon rotation of ratchet 35. It will be noted from Figure 3 that actuating member 40 and holding means 50 are mounted on shaft 20 between member 23 and boss 21 so that the force exerted by spring 60 is confined between retaining members 23 and 24, thereby permitting actuating member 40 to be oscillated freely on shaft 20.

Upon rotation of drum 15 by spring 13, in the

direction of the arrow indicated in Figure 2, pin 17 is rotated with said drum and upon each revolution of said drum strikes arm 42 to move it and actuating member 40 in a counterclockwise direction against the action of the resilient arm 45. The pivoting motion of member 40 by pin 17 flexes arm 45 so that it tends to straighten out, thereby increasing its effective length. As arm 45 straightens out, the inner end 47 rotates the ratchet 35 and the outer end 46 moves along block 18. Since arm 45 is resilient, it immediately assumes its original form after pin 17 has been moved past end 43 so that member 40 is returned to its normal position and inner end 47 is moved over ratchet 35 to pick up the next tooth. Arm 45 also serves to prevent retrograde movement of ratchet 45 in addition to maintaining member 40 in its normal position and intermittently advancing ratchet 35.

Since ratchet 35 is freely rotatable on shaft 20 and frictionally coupled thereto, the scale disc 28 can be rotated in either direction independently of said ratchet. As the scale disc 28 and shaft 20 are manually rotated as a unit in a clockwise direction, the ratchet is positively held against rotation by finger 47 and frictionally held against rotation by finger 53, but the scale disc and shaft are free to rotate, spring 60 allowing shaft 20 to slip when rotated in that direction. In the opposite direction, finger 47 has no effect and ratchet 35 rotates with disc 28 and shaft 20 against the action of finger 53. Pin 17 determines the amount of movement of arm 42, and, hence, the amount of flexing that is imparted to arm 45. Therefore, the number of teeth moved by arm 45 for each revolution of the drum for intermittently advancing ratchet 35 depends on the height of said pin. In the present embodiment, pin 17 is of such a height that ratchet 35 is rotated a single tooth for each revolution of the drum.

Since other varieties of the invention are possible, the scope of the invention is not to be limited in any respect by the present disclosure, but is defined in the appended claims.

Having now particularly described my invention what I desire to secure by Letters Patent of the United States, and what I claim is:

1. A ratchet type indicator comprising a driven member, an indicating means on said driven member and rotatable therewith, an intermediate drive member rotatably mounted on said driven member and having a toothed periphery, an actuating member pivotally mounted on said driven member and having an arm adapted upon movement thereof to pivot said actuating member and a second arm in engagement with said toothed periphery to prevent retrograde movement of said intermediate drive member and adapted upon movement of said first-mentioned arm to rotate said intermediate drive member, and resilient means frictionally engaging said driven member and said intermediate drive member for rotating said driven member upon movement of said first-mentioned arm and for permitting said indicating means to be rotated independently of said intermediate drive member.

2. A ratchet type indicator comprising a driven member, an indicating means on said driven member and rotatable therewith and including a graduated scale having a zero position, an intermediate drive member rotatably mounted on said driven member and having a toothed periphery, an actuating member pivotally mounted on said driven member and having an arm adapted upon

movement thereof to pivot said actuating member and a resilient arm in engagement with said toothed periphery to prevent retrograde movement of said intermediate drive member and adapted upon movement of said first-mentioned arm to rotate said intermediate drive member through a predetermined angle, and resilient means frictionally engaging said driven member and intermediate drive member for rotating said intermediate drive member upon movement of said resilient arm and for permitting said indicating means to be rotated in either direction for returning said scale to said zero position.

3. A ratchet type indicator comprising a driven member and including spaced retaining members, an indicating means on said driven member and rotatable therewith and including a graduated scale having a zero position, an intermediate drive member having a toothed periphery and rotatably mounted on said driven member and between said retaining members, an actuating member pivotally mounted on said driven member and having an arm adapted upon movement thereof to pivot said actuating member and a resilient arm in engagement with said

toothed periphery to prevent retrograde movement of said intermediate drive member and adapted upon movement of said first-mentioned arm to rotate said intermediate drive member through a predetermined angle, a holding means for frictionally engaging said toothed periphery to prevent retrograde movement of said intermediate drive member, and resilient means between said spaced retaining members for maintaining said intermediate drive member in frictional engagement with one of said retaining members for rotating said driven member upon movement of said first-mentioned arm and for permitting said indicating means to be rotated independently of said intermediate drive member.

EDWARD S. MCKEE.
